CLAIM

The ornamental design for a centralized control panel for a boat, as shown and described.

DESCRIPTION

FIG. 1 is a front elevational view of a centralized control panel for a boat showing my new design;

FIG. 2 is a top plan view thereof;

FIG. 3 is a left side elevational view thereof;

FIG. 4 is a right side elevational view thereof;

FIG. 5 is a bottom plan view thereof; and,

FIG. 6 is a rear elevational view thereof before the switches, fuses, lighter and power outlet are installed.
